CHAIR

Chester J. Barecki and Bror W. Henrikson, Grand Rapids, Mich., assignors to American Seating Company, Grand Rapids, Mich., a corporation of New Jersey

Filed Nov. 12, 1964, Ser. No. 82,554

Term of patent 14 years

(Cl. D15—8)

The dominant features of our design reside in the seat and back of the chair in which transverse recessed panels in the back and seat are in balanced relation and are provided with spaced holes simulating fastener openings.

We claim:

The ornamental design for a chair, as shown and described.
